UNITED STATES PATENT OFFICE

FRANK I. SHEAHAN, OF CHICAGO, ILLINOIS, ASSIGNOR TO M. H. DETRICK COMPANY, OF CHICAGO, ILLINOIS, A CORPORATION OF ILLINOIS

FURNACE-WALL CONSTRUCTION

Application filed June 16, 1928. Serial No. 286,049.

This invention relates to the construction of furnace or combustion chamber walls of the sort wherein fire brick or refractories are utilized to form the heat-resistant wall portion. It pertains particularly to an improved construction and structural elements for forming expansion joints in such walls which are sectionally supported.

Types of furnace walls are now known in which the heat-resistant or heat-confining wall of the furnace is made up of refractories, such as fire brick, so supported as to form conjoining sections arranged one above another, the respective sections being supported independently of those below them, with provision for accommodation of expansion of respective sections. Such constructions are designed particularly to avoid the heavy loading of lower portions of the refractory wall structure by the weight of super-imposed portions, and to avoid the subjection of the refractories to high compression such as might result from thermal expansion of the refractories when highly heated. The ultimate object, of course, is to increase the term of serviceability of the refractories by relieving them of forces such as result from the conditions just mentioned, which forces would contribute to distortion of the refractories and the walls and promote disintegration of the refractories incident to heating and cooling.

The present invention is concerned primarily with the provision of structural features for forming the expansion joints in such walls, and its general object is the provision of a construction and structural elements for forming the same which will contribute to the durability of the refractories involved in the expansion joint construction, accommodate the necessary expansion while maintaining closed joints between juxtaposed sections, and maintain the cooperating joint refractories in the desired relationship while at the same time permitting removal and replacement of refractories at the joint in the making of repairs without involving the removal of refractories from the superjacent section.

More specifically, one of the objects of the

invention is the provision of an improved joint construction and elements for forming it which will minimize the surface exposure of respective refractories to the wearing effects, such as slagging, which occur within the furnace chamber. 55

Another specific object of the invention is the provision of a joint construction and elements for forming same which will minimize the liability of the refractories to spalling. 60

Other and further objects of the invention will be pointed out or indicated hereinafter, or will appear to one skilled in the art upon an understanding of the invention or its 65 employment in practice.

In the drawing forming a part of this specification I illustrate certain forms of furnace wall construction and structural elements in which my invention may be embodied, but it is to be understood that these are presented for purpose of illustration as the invention as defined in the appended claims is susceptible of embodiment in forms and constructions differing in particulars 70 from those here shown and hereinafter described. 75

In said drawing

Fig. 1 is a detail of furnace wall construction showing a part interior elevation 80 of one wall and a part sectional elevation of an adjoining wall, the section being taken on a line approximating line A—A;

Fig. 2 is a detail in the nature of a part sectional elevation corresponding to the sectional part of Fig. 1 but showing the relationship of refractories at the joint consequent upon thermal expansion of the wall refractories; 85

Fig. 3 is a perspective view of one of the joint refractories; 90

Fig. 4 is a perspective view of another of the joint refractories;

Fig. 5 is a face view of one of the wall refractories illustrating the relationship 95 thereto of certain joint refractories, and

Fig. 6 is a perspective view of an anchoring element for joint refractories.

The nature of the invention will be most quickly ascertained by consideration of the 100

examples shown in the drawing. Let it be understood that the furnace wall construction here shown is generally of the type illustrated and described in U. S. Patent No. 5 1,747,822, to Raymond D. Foltz, assigned to M. H. Detrick Company. With such understanding, it will be recognized that the members designated 10 represent wall hangers which have vertically extending bar-like body portions with outwardly extending arms 10^a and 10^b at their upper and lower ends respectively, and lateral flanges 10^c along their inner margins above inwardly extending shelves 10^d. By means of the arms 10^a and 10^b the hangers are supported on suitable frame members, as disclosed in the application and the patent mentioned above, so that the hangers may be arranged collaterally in series, with the series one above 15 another, and the body portions of the hangers extending in a generally vertical direction. The respective horizontally running series of hangers support wall sections arranged one above another, the respective sections being made up each of a plurality of refractories so associated as to present a regular interior wall surface, which constitutes the fire surface of the chamber wall. These refractories, in the construction herein 20 illustrated, are of three forms, same comprising the overlying joint refractories 11, the underlying joint refractories 12 and flat refractories 14. The wall sections are composed for the most part of the flat refractories 14, a course of the overlying joint refractories 11 being employed at the bottom of each section, and a course of the underlying joint refractories 12 being employed at the top of each section. The flat refractories 14 and joint refractories 11 may be of the same 25 general face contour, such as that shown in Fig. 5, having parallel lateral sides arranged at right angles to their inner ends and with T-shaped slots S formed at the middle of their outer ends, which slots are of such size 30 as to accommodate the flanges 10^c and portions of the web of the hangers so that said flat refractories may be slipped on to said flanges at the upper ends thereof and thus afforded an anchoring engagement with the associated hangers. While each of the flat refractories 14 is of uniform thickness throughout, the joint refractories 11 are formed with an offset portion 11^a so that they are thinner 35 at the slotted end than at the opposite end, their opposite faces, however, being parallel. The offset 11^a is arranged at such a distance from the slot S as to accommodate the shelf 10^d of the hanger, so that when one of these refractories is positioned on the hanger as 40 above described, it may be slid down on the flanges 10^c until the thinner portion comes to rest on the shelf 10^d, whereat the offset portion 11^a will depend down across the inner margin of the shelf. The thinner portion

may be recessed as illustrated at 11^b to accommodate the shelf. A course of the refractories 11 being thus disposed on the hangers of a series, the section is built up to a requisite height with flat refractories 14 disposed in superimposed courses and having anchoring connection with the hangers as above explained. The top course of a section is composed of the underlying joint refractories 12, and these normally are placed 70 before the construction of the superjacent section is started, in the original assembly of the wall. For convenience in assembly, and also for durability, it is desirable that the refractories 12 be smaller in size than the refractories 11 and 14, and for convenience, their width may be some fractional part of the width of the refractories 14, such as one-half, one-third or one-fourth. They are most conveniently made of approximately the 75 same length as the refractories 11 and 14, with parallel opposite side faces meeting the inner end face at a perpendicular and with the bottom face perpendicular to the side and inner end faces. The top face is formed with an offset 12^a which is spaced from the inner end by a distance slightly greater than the corresponding spacing of the offset 11^a of the overlying joint refractories 11. At a distance 80 from the inner end corresponding to the spacing of the slots S in the refractories 11 and 14, the refractories 12 are provided with a transverse groove 12^b in the lower face, and the outer end preferably is beveled off somewhat in the fashion shown. The adjacent horizontal series of hangers are disposed in such relationship that the vertical distance between their shelves is such as to accommodate the course of refractories 11 and the desired number of courses of refractories 14 and leave a clearance between the top surface of the uppermost refractories 14 in engagement with the hangers of the lower series and the lower surface of the superjacent refractories 11, such as to accommodate 85 insertion of the refractories 12 therebetween from the inner side of the wall. This vertical clearance, therefore, is slightly in excess of the thickness of the refractories 12 between their bottom faces and the top face 90 of the offsets 12^a. The refractories 12 are inserted in the position illustrated in Fig. 1, in which there is a slight horizontal clearance between the offsets 12^a and 11^a, and the space between the lower faces of the thickened portions of refractories 11 and the upper face of the refractories 12 is filled with 95 a packing of compressible refractory material 15, such as a mixture of fire clay and asbestos. As a consequence of this arrangement, when the refractories of the subjacent section expand with heating, such expansion is accommodated by the yielding of the joint packing 15. Incident to this expansion, the offset 12^a is free to move upwardly across the 100 105 110 115 120 125

vertical face of the offset 11^a, as to a position illustrated in Fig. 2, thus giving a sliding contact between the juxtaposed faces of these offsets which maintains a closed joint 5 of tortuous form at the outer side of the packing 15. Thus the juxtaposed sections are given the desired freedom of movement at the expansion joint to accommodate expansion without subjecting each other to undesirable compression forces, and at the same 10 time the joint is maintained tight against leakage of air and flame.

As a means for anchoring the refractories 12 against displacement either inwardly or outwardly, anchoring members 16 are employed. These anchoring members are small iron castings having a seating lug 16^a adapted to fit in the slot of a refractory 14 and a holding portion 16^b adapted to rest upon and extend over a portion 20 of the upper face of the refractory 14 in parallel relationship to the slot. The holding portion 16^b is of size and form to be received in the grooves 12^b of refractories 12, 25 and preferably is of such length as to engage a plurality of such refractories resting on the refractories 14. By virtue of such engagement the refractories 12 thus engaged are held against displacement either 30 inwardly or outwardly of the wall, so that their inner end faces are held in alignment with the faces of the other wall refractories. It is not desirable that all the refractories 12 be thus anchored by the members 16, as such 35 would preclude the removal of the refractories from between the sections in making repairs or replacements. Consequently, the length of the holding members 16^b is such that there will be space for insertion of a 40 refractory 12 between those in engagement with adjacent anchoring members. Such an arrangement is illustrated in Fig. 5, wherein the positions of four of the refractories 12 are shown in dotted lines in relationship 45 to an underlying refractory 14. It will be observed that the two intervening refractories 12 will be engaged by the anchoring member 16, whereas the two outer refractories 12 will be free from the anchoring 50 members. These free refractories are held in position by their frictional contact with the refractories on which they rest and the anchored refractories 12 at opposite sides of them, and their inward displacement by expansion is prevented by their engagement 55 behind the offsets 11^a of overlying joint refractories, as illustrated in Fig. 2. In the original building of the wall, it is built from the bottom up, a lower section being 60 completed with the refractories 12 in place before the superjacent section is started. For the purpose of replacing refractories in a limited area of the wall after the furnace has been in operation, however, it may be 65 desirable to remove refractories in a lower

section without disturbing a superjacent section. In making such a replacement, one or more of the free refractories 12 may be knocked out, whereupon adjacent anchored refractories 12 may be slid laterally into the space thus afforded until clear of the end of the anchoring member, and then withdrawn from the wall. By removal of a sufficient number of the joint refractories 12 in this fashion, vertical space is afforded for 70 removal and replacement of underlying refractories 14 and 11. After replacement of 75 those refractories, the anchoring members 16 may be placed on the uppermost refractories 14 in the replaced portion, and the joint refractories 12 inserted into the wall between the anchoring members and slid laterally into engagement with them, the intervening spaces between the anchored refractories 12 being closed by insertion of 80 such refractories in the spaces between the anchoring members. Thus, it will be observed, replacements may be made with facility in any section without involving removal of refractories from a superjacent 85 section, and at the same time the various refractories are so anchored and retained in the wall as to prevent their displacement by 90 expansion and pulsations while the furnace is in operation. It will be understood, of course, that the fit of the various refractories on the flanges 10^c and on the anchoring members 16 is sufficiently free to allow 95 the refractories limited latitude of individual movement, so that they may accommodate 100 themselves to pressures without fracturing the portions in engagement with said parts.

By virtue of the accommodation for expansion afforded by the construction, and the avoidance of heavy loading of any of the refractories, and their limited freedom of individual movement and their form and relationship in the assembly, the conditions most conducive to spalling are 105 avoided, yet the wall is afforded secure support and is maintained definitely in alignment. Rapid wearing away of the refractories 11 and 14 by slagging is avoided by the cooling effect of the hangers, which, it 110 will be observed, have substantial areas embedded in the refractories and substantial areas exposed to air circulation outside the wall, whereby they exercise a certain heat-diffusing effect. The refractories 12 are not 115 afforded this cooling effect to the extent that the others are, as they do not have direct engagement with the hangers. It will be observed, however, that the areas of these refractories 12 which are exposed to air at 120 the outside of the wall are substantially greater than the areas exposed within the furnace chamber. This feature, together with the fact that these refractories 12 are 125 considerably smaller than the other refrac- 130

stories, practically equalizes the temperature of the refractories 12 with the others, with the result they are not subject to wear by slagging to a disproportionate extent. 5 Moreover, due to their smaller size, they may be given a harder burn in manufacture, and their liability to disintegration under conditions of furnace operation thereby reduced. The joint refractories 11, while having the greatest area exposed to the furnace fire, have at the same time the greatest area of contact with the heat-diffusing hangers, so that the temperature of their exposed surfaces is practically equalized with that 10 of the adjacent refractories. Consequently, by virtue of the construction and form of various structural elements, the tendency to more rapid wear or disintegration of refractories at the expansion joint which has been 15 observed in some constructions heretofore employed is effectively decreased.

A particular advantage in the present invention resides in the fact that the structural elements such as the refractories 11 and 12, standardized as to form and dimensions, may be employed quite generally in 20 walls of different sizes and furnaces of different designs, with the result that original and maintenance costs may be kept down 25 and repairs and replacements simplified and facilitated.

What I claim is:

1. A furnace wall structure comprising, in combination, refractories arranged to 30 form wall sections one above another, means for supporting respective sections independently, the refractories at the meeting margins of sections comprise overlying joint refractories and underlying joint refractories spaced vertically to afford an expansion joint, the underlying joint refractories having their outer ends of greater area than their inner ends so as to have greater surface exposure at the outer side of the wall 35 than at the inner side thereof, said underlying refractories being withdrawable horizontally from the wall while the overlying joint refractories are in place.

2. A furnace wall structure as specified 40 in claim 1 and wherein the overlying and underlying joint refractories have portions arranged to overlap in substantially perpendicular relationship to the expansion joint.

3. A furnace wall structure as specified 45 in claim 1 and wherein the overlying and underlying joint refractories have offset portions arranged to overlap upon thermal expansion of the wall sections, to close the expansion joint.

60 4. A furnace wall structure as specified in claim 1 and including means for anchoring respective overlying and underlying joint refractories in the wall to hold their inner end faces in the same plane.

5. A furnace wall structure comprising,

in combination, an underlying joint refractory, an overlying joint refractory supported independently of the underlying joint refractory and above the same with an intervening space to accommodate relative vertical expansion of the refractories, means for anchoring the overlying refractories in position, said underlying refractory having an upstanding projection adjacent its outer end, the overlying refractory having a depending portion adjacent its inner end, said portions arranged to overlap in an approximately vertical plane, the overlying joint refractory being removable horizontally inwardly from below the overlying joint refractory while the latter is anchored in place. 70 75 80

6. A furnace wall joint structure comprising correlated overlying and underlying joint refractories, the respective underlying joint refractories being larger at one end than at the other end, having parallel top and bottom face portions and formed with a transverse groove near one end of the bottom face portion and an upstanding offset portion on its upper side above said groove, the respective overlying joint refractories having parallel top and bottom faces and a T-shaped slot extending through one end perpendicular to said faces and an offset portion on its lower side of a length corresponding to the distance between the offset portion and the smaller end of the underlying joint refractories. 85 90 95

7. Joint elements for furnace walls comprising correlated overlying and underlying joint refractories which are thicker at one end than at the other and each having one plane end, respective overlying and underlying joint refractories having offset portions adapted to overlap in a plane approximately parallel to their plane ends, respective underlying joint refractories having parallel top and bottom faces and a transverse groove in the lower side near one end, 100 105 the respective overlying refractories having a T-shaped slot extending through one end in a direction approximately parallel with the plane end. 110

8. As an article of manufacture, a polyhedral furnace wall refractory having parallel side faces and opposite end faces and a bottom face perpendicular to the side faces and one of the end faces, the bottom side being provided with a transverse groove adjacent one end and the upper side of the refractory being formed with an upstanding transversely extending offset portion above the groove, the end of the refractory which is adjacent the groove having greater 115 120 125 surface area than the other end.

9. As an article of manufacture, a polyhedral furnace wall refractory having parallel side faces, a bottom face perpendicular thereto and an end face perpendicular to 130

said bottom and side faces and a top face portion parallel to the bottom face, said refractory being provided on its upper side with a transversely extending offset portion 5 extending upwardly from said top face portion and in its bottom with a transverse groove extending perpendicularly to the side faces and disposed near the end of the refractory opposite said end face.

10 10. In furnace wall structure, in combination, flat refractories each having its broader faces parallel and extending perpendicularly to a plane end face and a T-shaped slot extending through the end opposite said 15 end face, and joint refractories each of less width than the flat refractories but of approximately the same length as the latter, each of said joint refractories having its side faces parallel and a bottom face perpendicular 20 to the side faces and an end face perpendicular to the bottom face, said joint refractories each being provided with a transverse groove in its bottom side extending parallel to said end face and spaced therefrom by a distance corresponding to the 25 perpendicular distance between the plane end face and the head of the T-shaped slot, each of said joint refractories having an upstanding offset portion on its top side over 30 said groove.

11. Furnace wall structure as specified in claim 10 and wherein the width of the respective joint refractories is a fraction of the width of one of the flat refractories.

35 12. A furnace wall structure as specified in claim 1 and including shelf portions for supporting the wall sections, the overlying joint refractories having portions depending across the inner margins of said shelf 40 portions.

In testimony whereof I have hereunto subscribed my name.

FRANK I. SHEAHAN.
